RECORD DEVICE

Elmer B. Klein, St. Louis, Mo.

Application March 5, 1941, Serial No. 381,784

7 Claims. (Cl. 129—16)

This invention relates to record devices; and has special reference to holders for record cards adapted for engagement with the cards in a novel and convenient manner.

Objects of the invention are to provide an improved holder for a specially designed record card or sheet; to provide means for detachably connecting the holders to form a longitudinal series thereof; and to provide record cards or sheets having physical elements or parts adapted to engage the respective holders for suspension thereby and also in a manner to prevent disarrangement of the cards or sheets relative to themselves or to the holders.

Another object of the invention is to provide an improved holder for a record card or sheet having a supporting portion for engagement with said card or sheet and retaining portions for engaging the upper edge of the card or sheet laterally from the supporting portion in order to hold the card or sheet in proper relationship and prevent displacement thereof.

Another object of the invention is to provide an improved record card or sheet adapted for detachable engagement with the holder so that the cards or sheets may be connected with the holder, and removed therefrom for filing or other purposes, in order to meet business requirements or conveniences.

Other objects will appear from the following description, reference being made to the annexed drawing illustrating a suitable embodiment of the invention and in which—

Fig. 1 is a front elevation of a series of record cards or sheets attached to connected holders, parts of the cards being broken away to show the holders therefor and also to disclose clearly the manner in which the cards are attached to the holders.

Fig. 2 is a side elevation showing two series of card or sheet holders and record cards or sheets attached thereto supported in back-to-back relationship by a single supporting member.

Fig. 3 is a perspective view of a holder made in accordance with the present invention.

Fig. 4 is an elevation or plan view of a portion of a record card or sheet having a slot specially provided therein for engagement with the holder, and a hinge device spaced from said slot permitting the card or sheet to be folded or turned over to expose the next subjacent card or sheet.

Each card holder is preferably composed of a section of sheet metal or the like formed to provide a flat body portion 1, a forwardly curved and upwardly extended hook 2 at the middle of

10 the lower edge of the body portion, a slot 3 along the upper margin of the body portion parallel with the hook 2 and at least as long as said hook, and a forwardly and downwardly turned hook 4 at each end of the body. A series of these hangers may be linked together as shown in Figs. 1 and 2 by engaging the hooks 2 in the slots 3 of the respective card holders to provide a pivotally connected series or chain of the holders.

Each record card or sheet 5 is of the size desired and is formed with a slot 6 near and parallel with its upper edge. The slot 6 in each card or sheet 5 is arranged at such a distance from the upper edge thereof that, when the slot 6 is engaged with the hook 2, the upper edge of the card will engage rather closely within and against the hooks 4, thereby positively preventing accidental detachment of the respective cards from the holders to which they are attached, and also preventing substantial displacement thereof. Each card is also formed with a longitudinal hinge 7 below and parallel with the slot 6 and the upper edge of the card, so that each card may be turned upwardly or backwardly about said hinge to expose the next subjacent card for the purpose of inspection or for the purpose of receiving additional records.

These hangers may be connected together in continuing series to any extent or length desired and may be detached optionally. When the hangers are connected in extended series, each record card or sheet is attached to the hook 2 in front of the next lower hanger engaged with said hook.

As shown in Fig. 2, two series of holders or hangers may be suspended by a single device 8 provided with oppositely disposed and upwardly extended hooks 9 for engagement in the slots 3 of the uppermost hangers of the two series. The device 8 may also be formed with a hole to receive a supporting rod 10 along which said device may be moved so that any desired number of longitudinal series of record cards or sheets and hangers therefor may be suspended from the same rod.

A V-shaped connector 11 may be engaged with the hooks 2 of the lowest card holders or hangers of the two series thereof that are suspended back-to-back from the same device 8. The connector 11 will hold the lower ends of the two series of hangers or holders close to each other while the upper ends thereof are held close to each other by the device 8 which suspends them.

From the foregoing it is apparent that this

invention attains all of its intended objects and purposes quite efficiently and economically. The hangers are readily interchangeable, as are the record cards or sheets, so that no inconvenience is encountered in reassembling them after they have been detached. The specific form, construction and arrangement of the parts may be varied within equivalent limits without departure from the nature and principle of the invention as defined by the appended claims.

I claim:

1. A holder for a record card or sheet comprising an elongated body having an opening intermediate of its ends and near its upper edge for engagement with a support, an upturned hook in connection with said body below said opening adapted to extend through a card or sheet to be held by said holder, and a pair of downwardly extended hooks in connection with said body below the upper wall of said opening and above the horizontal plane of said first hook adapted to engage the upper longitudinal margin of the card or sheet that is attached to said first named hook.

2. A holder for a record card or sheet comprising a thin elongated body having an opening intermediate of its ends and near its upper edge for engagement with a support, an upturned hook in connection with the lower longitudinal portion of said body below said opening adapted to extend through an opening in a card or sheet to be held by said holder, and a pair of downwardly extended hooks in connection with said body below said opening and above the horizontal plane of said first hook adapted to extend in front of the upper longitudinal margin of the card or sheet that is mounted on said first hook and to prevent substantial turning of said card or sheet about said first hook.

3. A holder for a record card or sheet comprising an elongated body having an upturned hook in connection therewith below its upper edge and adapted to extend through a card or sheet to be suspended by said holder, a pair of downwardly extended hooks in connection with said body disposed laterally beyond the vertical edges of said first hook and adapted to engage the upper longitudinal edge and the front of the upper longitudinal margin of the card or sheet that is engaged by said first hook, and an upward extension integral with said body between said last named hooks and having an

opening above a line connecting said hooks for engaging a support.

4. Record devices comprising a vertical series of holders having direct pivotal engagement with each other, means in connection with the holder at the upper end of the series for suspending said upper holder and thereby said entire series of holders, a record card or sheet detachably connected with each holder, and hooks in connection with each holder engaging the upper longitudinal margin and edge of the card or sheet attached thereto.

5. Record devices comprising a vertical series of holders, means providing direct pivotal connection of each holder to another holder of the series, means in connection with the holder at the upper end of the series for suspending said upper holder and thereby said entire series of holders, a record card or sheet detachably connected with each holder, hooks in connection with each holder engaging the upper longitudinal margin and edge of the card or sheet attached thereto, and a device for suspending two series of said holders and cards or sheets back-to-back.

6. Record devices comprising a series of pivotally connected holders, means in connection with the holder at one end of the series for suspending said series of holders, a record card or sheet detachably connected with each holder, hooks in connection with each holder engaging the upper longitudinal margin and edge of the card or sheet attached thereto, a device for suspending two series of said holders and cards or sheets back-to-back, and means for connecting the lower ends of said series of holders in a manner to prevent substantial relative movement thereof.

7. A record device comprising a holder having an upturned hook in connection with one side portion thereof, a pair of downwardly extended hooks above the longitudinal axis of said first hook and laterally beyond the vertical edges thereof, a record card or sheet having a slot through which said first hook extends and having its upper longitudinal margin extending under said second hooks and its upper edge engaged thereby, and a central upwardly extended portion integral with said body having an opening above said card or sheet and between the vertical innermost edges of said last named hooks for engaging a support to suspend said holder.

ELMER B. KLEIN.
